CLAIM

The ornamental design for a handguard, as shown and described.

DESCRIPTION

FIG. 1 is an isometric view of a handguard positioned about a barrel assembly of an auto-loading firearm.

FIG. 2 is an elevation view of one end of the handguard of FIG. 1, the other end being identical.

FIG. 3 is an elevation view of one side of the handguard of FIG. 1, the other side being identical.

FIG. 4 is a top plan view of the handguard of FIG. 1.

FIG. 5 is a bottom plan view of the handguard of FIG. 1.

FIG. 6 is a cross-sectional elevation view of the handguard along lines 6-6 of FIG. 3.

FIG. 7 is a cross-sectional side view of the handguard along lines 7-7 of FIG. 2, the other side being a mirror image; and, FIG. 8 is a cross-sectional side view of the handguard along lines 8-8 of FIG. 2, the other side being a mirror image.

The broken lines in the figures are used to illustrate environment and unclaimed parts and form no part of the claimed design.
